UNITED STATES PATENT OFFICE.

LAWRANCE N. DAVIS, OF CHARLOTTE, NORTH CAROLINA.

SAFE.

No. 903,456.

Specification of Letters Patent.

Patented Nov. 10, 1908.

Application filed July 3, 1908. Serial No. 441,852.

To all whom it may concern:

Be it known that I, LAWRENCE N. DAVIS, a citizen of the United States, residing at Charlotte, in the county of Mecklenburg and State of North Carolina, have invented a new and useful Safe, of which the following is a specification.

This invention relates to kitchen safes.

The object of the invention is to dispense entirely with the use of bolts or screws in holding the various parts of the article assembled and in lieu thereof to connect the parts by the employment of dowel pins carried by certain of the members and to engage orifices formed in other of the members, all the parts of the safe being held set up by the shelves, the top of the safe being closed by a panel having means to preclude entrance of rain or dust.

With the above and other objects in view, as will appear as the nature of the invention is better understood, the same consists in the novel construction and combination of parts of a knock-down safe, as will be hereinafter fully described and claimed.

In the accompanying drawings forming a part of this specification, and in which like characters of reference indicate corresponding parts, Figure 1 is a view in perspective of the safe, showing certain of the parts thereof disconnected. Fig. 2 is a front elevation, partly in section of the safe.

The safe embodies a back wall 1, a front wall 2, two end walls 3 and 4, two shelves 5 and 6, and a top 7. The back wall 1 has secured to its two longest edges two pairs of strips 8 and 9, each pair of which constitutes one leg. The strips 9 are each provided with two orifices 10 to receive dowel pins 11 carried by the end walls 3 and 4. The front wall 2, which also carries the doors 12 has secured to its two longest edges two pairs of strips 13 and 14, the strips 14 being provided with two orifices 15 to receive the dowel pins 11 carried by the end walls 3 and 4 in the same manner as the back wall. Each of the end walls is a counterpart of the other, and each has secured on its outer sides and its upper and lower ends two battens 16 and on its inner sides two transverse battens 17 that constitute rests for the shelves 5 and 6. The top 7 has secured to its under side two bands of molding 18 and 19 that are designed to fit snugly on the inner side and outside of the upper edges of the four walls, and thereby preclude entrance of moisture or dust from the top of the safe.

In assembling the parts of the safe, the dowel pins of the two end walls are brought into engagement with the orifices in the back and front walls, and the shelves are then inserted to position, and by bearing against the inner faces of the end walls will serve to hold all of the parts of the structure securely assembled. The top is now positioned thus completing the setting up of the article.

While not essential, screws or nails may be employed to secure the top in place, and thus measurably increase the stability of the article.

I claim:

1. A safe comprising back, front and end walls, certain of the walls being provided with dowel pins to engage orifices in the other walls, shelf rests secured to the inner faces of the end walls, and shelves engaging the rests and operating to hold the structure set up.

2. A safe embodying back, front and end walls, certain of the walls being provided with dowel pins to engage orifices in the other walls, rests secured in the inner surfaces of the end walls, shelves to engage the rests and bear against the end walls to hold the structure assembled, and a top having spaced molding to engage with the upper ends of the walls.

In testimony that I claim the foregoing as my own, I have hereto affixed my signature in the presence of two witnesses.

LAWRENCE N. DAVIS.
